(57) **CLAIM**

The ornamental design for an instrument for analyzing specimen containers, as shown and described.

DESCRIPTION

FIG. 1 is a left and front perspective of an instrument for analyzing specimen containers showing the design;

FIG. 2 is a front elevation view thereof;

FIG. 3 is a right and front perspective view thereof;

FIG. 4 is a left side elevation view thereof;

FIG. 5 is a right side elevation view thereof; and,

FIG. 6 is a top plan view thereof.

The broken lines in the drawing views are included for the purpose of illustrating portions of the instrument for analyzing specimen containers that forms no part of the claimed design.
